UNITED STATES PATENT OFFICE.

JOHN MANNING VAN HEUSEN, OF JAMAICA PLAIN, MASSACHUSETTS, ASSIGNOR TO
VAN HEUSEN PRODUCTS, INC., A CORPORATION OF DELAWARE.

FOLDING COLLAR.

Application filed November 10, 1921. Serial No. 514,165.

To all whom it may concern:

Be it known that I, JOHN MANNING VAN HEUSEN, a citizen of the United States of America, residing at No. 33 Lakeville Place, 5 Jamaica Plain, in the county of Suffolk, State of Massachusetts, have invented certain new and useful Improvements in Folding Collars; and I do hereby declare the following to be a full, clear, and exact description of the invention, such as will enable others skilled in the art to which it appertains to make and use the same.

This invention relates to improvements in collars made of heavy fabric such as multiple ply interwoven fabric and having a weakened fold or fold portion of increased flexibility woven therein. More particularly, it relates to such a fabric which can be woven as a straight fabric, as distinguished from a curvilinear fabric, but which may, nevertheless, have a fold portion of a generally curvilinear shape woven therein. The present invention, accordingly, provides a generally curvilinear fold portion without weaving the fabric as a whole with a curvilinear weave.

The collar fabric of which the collars of the present invention are made is woven with a series of relatively short, narrow portions of modified weave, which are so arranged with respect to each other that, taken together, they form a generally curvilinear portion of the fabric. The number and arrangement of such narrow portions of modified weave may be varied, for example, by varying the length of such portions or their width, or their arrangement with respect to each other, so that the general curvilinear form produced by a series of such portions may have a greater or less curvature, and so that the curvature may be varied and regulated in accordance with that desired for different collars, for example, for collars of different sizes or different styles.

The collar fabric may be woven in strips of a width equal to or somewhat greater than the width of the collar or it may be woven of a width such that a series of collar blanks may be cut therefrom across its width. In order that a series of collar blanks may be cut from a single piece of the fabric, the portions of modified weave

forming the generally curvilinear fold portions of the collars may be so arranged that 55 a maximum number of collar blanks can be cut from a piece of fabric of given size.

In weaving the fabric so that a series of collar blanks may be cut therefrom, the modified weave portions are arranged at 60 recurring intervals, spaced apart a sufficient distance to permit the cutting of the collar blanks with the modified portions at the fold lines thereof.

The invention will be further illustrated 65 in connection with the accompanying drawings, in which

Fig. 1 shows in perspective a finished collar embodying the invention.

Fig. 2 shows the collar unfolded and with 70 the modified weave portions indicated in dotted lines.

Fig. 3 is a sectional view of the collar taken on the line 3-3 of Fig. 2, and illustrating one form of weave and modified 75 weave of the fabric.

Fig. 4 is a similar view to that of Fig. 3, showing a modified weave.

Fig. 4^A is a cross-section of a modification similar to Fig. 4. 80

Figs. 5, 6 and 6^A are enlarged views illustrating the weaves and modified weaves of the fabrics of Figs. 3 and 4.

Fig. 7 shows a narrow fabric from which the collar blanks may be cut, with the collar 85 blanks indicated thereon.

Fig. 8 shows a wide fabric of a width equal to that of several collar blanks, and with the collar blanks indicated thereon.

The collar illustrated in Figs. 1 to 3 is 90 a one piece folding or turn-down collar made up of the neckband portion 1, and folding or turn-down portion 2, united at the fold line, which is of generally curvilinear shape or contour. The fabric illustrated in Figs. 95 3 and 5 is a two-ply interwoven fabric, woven with the upper and lower plies interwoven by interweave threads indicated at 4, the longitudinal warp threads of the fabric being indicated at 5, and the transverse 100 or weft threads at 6.

The collar illustrated in Figs. 4 and 6 is made up of three-ply interwoven fabric with the middle ply interwoven respectively with each outer ply, the two sets of interwoven threads 7 and 8 interweaving the two 105

adjacent plies of the fabric in the manner illustrated. The longitudinal or warp threads are indicated at 9 and the weft threads at 10. Along the fold line of the 5 collar, the fabric is woven with a series of narrow portions somewhat staggered with respect to each other, and which may overlap each other for a portion of their widths where they come together, but which, taken 10 together, form a generally curvilinear portion at which the collar folds.

The collar fabric from which the collar blanks may be cut is illustrated in Figs. 7 and 8. In weaving the fabric, the loom is 15 provided with an extra number of harnesses or heddles to provide for the modification of the weave of the fabric at the different transverse portions thereof, where it is desired to modify the weave. For example, 20 in the case of a two-ply interwoven fabric, the heddles which operate the interweave threads may be divided up so that the interweave threads of short portions of the fabric near the middle can be operated or 25 maintained inoperative. In weaving a fabric such as illustrated in Fig. 7 with a series of nine successive narrow portions per collar, two of which are indicated at 12 and 13 of Fig. 7, arranged lengthwise of the 30 fabric in the manner illustrated, it will be seen that there are seven different places across the width of the fabric near its center, where the weave is modified at successive periods in the weaving operation. That 35 is to say, starting from the segment or narrow portion midway between the collar blanks outlined in Fig. 7, it will be noted that there are seven successive segments to the center or highest point in the curved 40 fold line, each segment slightly displaced in the same lateral direction with respect to the preceding segments. For example, when the fabric is being woven at the part corresponding to the modified section 12, 45 the warp interweave threads for this narrow section may be carried through the fabric lengthwise of the said section 12 as filler threads, leaving the two outer plies of fabric continuous but not interwoven at this 50 portion. When the fabric has been woven to the end of the portion 12, the said warp interweave threads are then operated in the usual way to interweave the two plies of fabric in the same manner in which it is 55 elsewhere interwoven, while the interweave threads corresponding to the next modified weave portion 13, will be thrown out of operation and carried through as filler threads, thus leaving the portion 13 of the fabric 60 on each side disconnected. By regulating the interweave threads which are thrown out of operation in this way, the fabric can be provided with the modified weave at the short narrow portions indicated, and these 65 narrow portions can be arranged in the

manner illustrated and made of suitable length and width and with such relation to each other in the fabric that, taken together, they form a portion of generally curvilinear contour which, by reason of the omission of the interweave, will be more flexible than the portions on each side where the two plies are interwoven. 70

In the case of a wider fabric, such as illustrated in Fig. 8, the fabric may be woven in a similar way, with the provision of additional heddles for controlling part of the warp threads where it is desired to modify the weave of the fabric. In this case, however, where a series of collar blanks are to be cut from a single width of fabric, the heddles for the corresponding transverse portions where the weave is to be modified may be operated simultaneously. The weaving operation otherwise may be generally similar to that above described in the case of a narrow fabric. 75

It will be noted that in Figs. 6 and 6^a a three ply fabric is illustrated, the three plies being integrally bound together by two sets of interweave threads 7 and 8. The interweave thread 7 binds together the upper and intermediate plies, while the interweave thread 8 binds together the lower and intermediate plies. In weaving the 80 relatively short, narrow portions or segments of modified weave, it will be obvious that the intermediate threads 7 may be run as longitudinal filling threads through the said portion of modified weave, or the 85 interweave thread 8 may be run through the fabric as a longitudinal filler thread at the said portion, or both of the interweave threads may be run through the said portion as longitudinal filler threads, e. g., as illustrated in Fig. 6. It will thus be possible for the outer two plies, for example, to be interwoven while the inner ply and the intermediate ply are left separated, as illustrated, for example, in Fig. 6^a, thus providing the modified weave which is desired in 90 this relatively short, narrow portion. 95

In the foregoing specification and in certain of the appended claims I have used the term "modified weave" in describing the change in the weave of the collar fabric along the fold portion. By the term "modified weave" I mean a change or alteration in the weave of the fabric that results in the fold portion having a greater or less degree of flexibility than the main portion of the fabric. That is to say, I do not wish to limit my invention to a collar having a fold portion woven as hereinbefore set forth, the said fold portion having a greater flexibility 100 than the main portion of the fabric. 105

While I have illustrated and described in the drawings and specification a two and a three ply fabric having their plies interwoven in a certain manner, I do not limit 110

myself to a two or a three ply fabric or to the particular method of interweaving shown.

I claim:

- 5 1. A folding or turn-down collar made of a single piece of heavy fabric and having a natural fold portion provided by a series of relatively short, narrow portions of modified weave which are so arranged 10 with respect to each other that, taken together, they form a generally curvilinear fold portion in the collar.
- 15 2. A folding or turn-down collar made up of a single piece of multiple ply interwoven fabric, having a natural fold portion provided by a series of relatively short, narrow portions of modified weave which are so arranged with respect to each other that, taken together, they form a generally curvi- 20 linear fold portion in the collar.
- 25 3. A folding or turn-down collar made of a single piece of multiple ply interwoven fabric, having a natural fold portion of increased flexibility provided by a series of relatively short, narrow portions which are so arranged with respect to each other that, taken together, they form a generally curvilinear fold portion in the collar, one or 30 more of the interweave threads, which nor-

through as filler threads at the said relatively short, narrow portions, leaving one or more of the plies separate from the remaining ply or plies.

4. A folding or turn-down collar made up 35 of a neckband portion and a folding or turn-down portion, the said folding or turn-down portion being of a heavy fabric possessing sufficient inherent stiffness to give shape to the collar, and having a natural 40 fold portion provided at its upper edge by a series of relatively short, narrow portions of modified weave which are so arranged with respect to each other that, taken together, they form a generally curvilinear 45 fold portion.

5. A folding or turn-down collar made up 50 of a neckband portion and a folding or turn-down portion, the said folding or turn-down portion being of multiple ply interwoven fabric and having a natural fold portion provided at its upper edge by a series of relatively short, narrow portions of modified weave which are so arranged with respect to each other that, taken together, they 55 form a generally curvilinear fold portion.

In testimony whereof I affix my signature.

JOHN MANNING VAN HEUSEN.
